IMPLANTABLE MEDICAL-ELECTRONIC CARDIAC PACER UNIT

Howard J. Thompson, New Richmond, Wis., assignor to
Medtronic, Inc., Minneapolis, Minn.

Filed Apr. 26, 1974, Ser. No. 464,486

Term of patent 14 years

Int. Cl. D24—03

U.S. Cl. D83—1 F

Fig. 1

Fig. 2

Fig. 3

Fig. 4

Fig. 5

Fig. 6

FIG. 1 is a front view in perspective of implantable medical-electronic cardiac pacer unit, showing my new design;

FIG. 2 is a front elevational view thereof;

FIG. 3 is a right side elevational view thereof;

FIG. 4 is a left side elevational view thereof;

FIG. 5 is a top elevational view thereof; and

FIG. 6 is a bottom elevational view thereof.

The rear-elevational view of my new design is the identical mirror image of the front elevational view thereof depicted in FIG. 2.

I claim:

The ornamental design for an implantable medical-electronic cardiac pacer unit, as shown and described.
